ALDEN D. BLAKE, OF DETROIT, MICHIGAN.

DISAPPEARING BED.

1,099,962.

Specification of Letters Patent. Patented June 16, 1914.

Application filed April 22, 1914. Serial No. 833,580.

To all whom it may concern:

Be it known that I, ALDEN D. BLAKE, a citizen of the United States of America, residing at Detroit, in the county of Wayne and State of Michigan, have invented certain new and useful Improvements in Disappearing Beds, of which the following is a specification, reference being had therein to the accompanying drawings.

10 The invention relates to folding beds of that type in which the bed frame is connected to a carrier, by means of which it may in collapsed position be swung into a closet or other place of concealment.

15 It is the object of the present invention to obtain a construction of carrying or transporting means by which the collapsed bedstead may be quickly and easily removed to its point of concealment, and further to 20 obtain a construction which permits of readily attaching or detaching the bed from the carrier.

To this end the invention comprises the construction as hereinafter set forth.

25 In the drawings: Figure 1 is a side elevation showing the bed frame in extended position; Fig. 2 is a plan view showing the carrier collapsed and the folded bed in position of concealment, also indicating in dotted 30 lines the intermediate position of transportation; Fig. 3 is a detail illustrating the construction of the carrier and the manner of detachably engaging the same with the bed frame; and Fig. 4 is an enlarged detail view.

35 A is a collapsible or foldable bed of any suitable construction, not shown in detail; B is the head-board or foot-board of the bed; and C is the carrier or transporting device, 40 by means of which the folded bed is transferred to the place of concealment. This carrier C is constructed of a series of parallelogram levers or what is sometimes termed a lazy-tong, the arrangement being such as 45 to permit of a longitudinal extension or contraction while affording support for the load. The inner end of the carrier C is attached to a suitable anchorage such as a vertical rod D secured to the wall E by brackets 50 F. To this anchorage the cross connected end levers G and G' are secured so as to be capable of a pivoting action, and one of the levers, such as the lever G' is also permitted 55 a vertical sliding movement on the rod D.

55 In detail H is a sleeve slidably secured upon the rod D, having an outwardly-projecting

ear H' which is pivotally attached to the lever G', and H² is a similar sleeve having the ear H³ pivotally attached to the lever G. The outer end of the carrier C is detachably secured to the head or foot-board B, preferably by mounting upon the latter a vertical rod I having sleeves J and J' engaging the same. One of the sleeves, such as the upper sleeve J, forms a bearing for supporting the load, while the other sleeve slidably engages the rod I. Both sleeves have a detachable swivel engagement with the carrier C, preferably by providing them with bifurcated ears J², having a knuckle engagement with ears K on the pivotal fittings K' for the end levers G² and G³. Thus the ears K may be engaged between the bifurcated ears J² and secured by a pivot pin L.

With the construction as described in use, 75 when the lazy-tong carrier C is extended, as shown in Fig. 1, the ears K of the outer levers G² and G³ are in position for engagement with the bifurcated ears J² of the sleeves J and J', the bed being in extended 80 or opened-out position. When thus engaged, the bed may be collapsed or folded, and by then moving it forward the lazy-tong carrier will be shortened so as to transport the bed into the place of concealment. During this 85 movement the weight of the bed is supported by the carrier while the swivel connection between the ears K and bifurcated ears J², as well as the swivel connection of the sleeves H upon the rod D, will permit the 90 turning of the collapsed bed to pass through a narrow doorway. The placing of the load upon the carrier may be effected either upon the collapsing or folding of the bed, or if desired the lazy-tong carrier may be so arranged that as it is contracted in length the outer end will be slightly raised. The latter would be the case with the construction as shown in Fig. 1, in which the load of the bed is directly carried through the upper 100 sleeve J or the lever G², while at the opposite end of the carrier the load is transmitted through the lower sleeve H² to the bracket F for the anchor rod D. This permits the upper sleeve H at the inner end of the carrier and the lower sleeve J' at the outer end of the carrier to travel upon their respective rods, the result being that as the carrier is extended its outer end is lowered, while the contraction of the carrier will raise the outer 105 end.

To permit the movement of the sleeves

upon the rods D and I without the necessity of lubrication, roller bearings M are preferably secured thereto for engagement with the rods.

5 To assist in the movement of the transporting carrier, I preferably provide a tensioning device, such as the spring N which at one end is suitably anchored, as at O, and at the opposite end is attached to the 10 carrier, as at P. By means of this spring whenever the lazy-tong lever is extended the spring will be placed under tension, which will assist in the work of lifting the bed and transporting it to its position of conceal- 15 ment.

Upon occasions it may be desirable to leave the bed in extended position and to detach the transporting carrier therefrom. The operation of detachment is facilitated 20 by the provision of means for relieving the tension of the spring N during detachment. As shown, I have provided a yoke or spanner Q, which may be engaged with the opposite pivotal connections of the lazy-tong 25 lever to prevent a lateral movement thereof. This yoke is so proportioned as to be engageable with the carrier in the extended position thereof and while yet attached to the bed, and by reason of the fact that it 30 prevents the levers from expanding laterally, longitudinal movement in collapsed position is also prevented. Thus the tension of the spring N will be relieved and the ears 35 of the fittings K may be readily detached from the bifurcated ears J² of the fitting J. After the carrier is detached from the bed the yoke may be removed to permit of collapsing and storing the carrier, and whenever it is desirable to re-attach the carrier 40 to the bed it may be again extended and engaged with the yoke so as to hold the fittings in position of registration for attachment to the bed. In specific construction the yoke Q is provided with pins Q' which 45 engage apertures in the pivotal connection of opposite ends of the lazy-tong levers, as shown in Fig. 3.

What I claim as my invention is:—

1. The combination with a collapsible bed, 50 of a transporting carrier therefor comprising a longitudinally contractible and extensible supporting arm, an anchor connection for one end of said arm, and means for supporting the bed at the opposite end of said 55 arm.

2. The combination with a collapsible bed, 60 of a transporting carrier therefor comprising a longitudinally extensible and contractible supporting arm, an anchor support to which the inner end of said arm is pivotally attached, and a pivotal connection between the bed and the outer end of said arm.

3. The combination with a collapsible bed, 65 of a transporting carrier therefor, comprising a lazy-tong extensible arm, an anchoring support for the inner end of said arm, and a supporting connection between the outer end of said arm and said bed.

4. The combination with a collapsible bed, 70 of a transporting carrier therefor comprising a lazy-tong extensible arm, an anchoring connection for the inner end of said arm and to which it is pivotally attached, and a swivel supporting connection between the 75 outer end of said arm and said bed.

5. The combination with a collapsible bed, 80 of a transporting carrier therefor comprising a lazy-tong extensible supporting arm, an anchor connection for the inner end of said arm, and a detachable connection between the outer end of said arm and said bed.

6. The combination with a collapsible bed, 85 of a transporting carrier therefor comprising a lazy-tong extensible supporting arm, an anchor connection for the inner end of said arm, a connection between the outer end of said arm and said bed, and means for supporting the load of said collapsible bed upon said arm during the collapsing movement.

7. The combination with a collapsible bed, 90 of a transporting carrier therefor, comprising a lazy-tong extensible supporting arm, an anchor connection for the inner end of 95 said arm, a connection between the outer end of said arm and the bed, and resilient means for assisting in transporting the bed upon said carrier.

8. The combination with a collapsible bed, 100 of a transporting carrier therefor, comprising a lazy-tong extensible supporting arm, an anchor connection for the inner end of said arm, a detachable connection between the outer end of said arm and the bed, a 105 tension device for collapsing said arm and assisting in carrying the load of the bed, and means for locking said transporting arm from collapsing during attachment to and detachment from the bed. 110

9. The combination with a collapsible bed, 115 of a transporting carrier therefor, comprising a lazy-tong extensible supporting arm, an anchor connection for the inner end of said arm, a detachable connection between the outer end of said arm and the bed, and a yoke for spanning the space between opposite pivotal connection of the lazy-tong, to hold the same from movement during attachment to or detachment from the bed. 120

In testimony whereof I affix my signature in presence of two witnesses.

ALDEN D. BLAKE.
